US0D1001551S

(12) United States Design Patent (10) Patent No.: US D1,001,551 S
(45) Date of Patent: * Oct. 17, 2023

(54) BOOSTER CUSHION

(71) Applicant: Shenzhen Kunzhiyao E-commerce Technology Co., Ltd., Guangdong (CN)

(72) Inventor: Gang Li, Guangdong (CN)

(73) Assignee: Shenzhen Kunzhiyao E-commerce Technology Co., Ltd., Guangdong (CN)

() Term: 15 Years

(21) Appl. No.: 29/799,050

(22) Filed: Jul. 12, 2021

(51) LOC (14) Cl. 06-09

(52) U.S. Cl.

USPC D6/601; D6/333

(58) Field of Classification Search

USPC D6/333, 595, 596, 597, 601, 603, 604, D6/606, 610; D21/803, 804; D24/183, D24/184, 190

CPC .. A47G 9/0246; A47G 9/0253; A47G 9/0238; A47C 31/105

(57) CLAIM

The ornamental design for a booster cushion, as shown and described.

DESCRIPTION

FIG. 1 is a front, right, and top perspective view of a booster cushion, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right, and top perspective view of a first part of the booster cushion of FIG. 1, and a rear, right, and top perspective view of a second part of the booster cushion of FIG. 1, where the first part and the second part are disassembled.

The broken lines shown in the drawings are included for the purpose of illustrating portions of the booster cushion that form no part of the claimed design.

1 Claim, 9 Drawing Sheets
